Application June 30, 1950, Serial No. 171,424

10 Claims. (Cl. 246—63)

This invention relates to railway signalling systems and more particularly pertains to a cab signalling organization providing a display of signal aspects on a train to correspond to traffic conditions.

In territories where cab signalling is to be used, current pulses occurring at distinctive rates are generally applied to the rails of the track sections. Each code rate corresponds to a particular signal condition with the complete absence of pulses corresponding to the most restrictive indication. These pulses of current cause receiving and decoding apparatus on the train to be intermittently energized by the inductive transfer of coded track current energy with the rate of such energization corresponding to the coding rate of the track current. The decoding apparatus then selectively responds to the rate of its energization and controls the cab signal causing it to display the proper signal aspect.

On some railroads the current in the tracks is direct current, and on other railroads alternating current is used to energize the track circuits. On other railroads, the track current may consist of rectified but unfiltered alternating current with the rectification being either full-wave or half-wave. Various other railroads may have different kinds of track circuit energization in different localities. Thus, a portion of a railroad may employ direct current or rectified alternating current and an adjoining territory may have alternating current track circuits. It is desirable, however, that the train-carried apparatus be operable over the entire railroad regardless of the kind of track circuit energization employed in the various portions of the railroad. Therefore, the code detecting and receiving apparatus of the present invention includes means for permitting proper operation with either alternating current, direct current, or rectified alternating current track circuit energization. A two-position changeover switch is provided to cause the circuit organization to conform with the particular kind of track circuit energization encountered. With the switch in one position, the apparatus is conditioned to operate in regions of direct-current or rectified alternating-current track circuit energization; whereas, with the changeover switch in the other position, the apparatus is conditioned to operate in regions where the track circuits are energized with alternating current.

In addition to the adaptability of this apparatus to different kinds of track circuit energization, additional features are included to prevent the display of a signal indication less restrictive than stop under various conditions of failure of the apparatus. Thus, the use of two channels of amplification, for example, prevents improper operation in the event that various connections are intermittently broken. Also, stray currents in the track rails are prevented from causing operation of the code detecting apparatus because of trap circuits included in the circuit organization.

Other objects, purposes, and characteristic features of the present invention will be in part obvious from the accompanying drawings and in part pointed out as the description of the invention progresses. In describing

the invention in detail reference will be made to the accompanying drawings in which:

Fig. 1 diagrammatically illustrates a portion of railroad track in which various kinds of track circuit energization have been shown in adjoining track sections; and

Figs. 2A, 3A and 4A each show an embodiment of the code receiving and decoding apparatus of this invention and the associated wave form diagrams of Figs. 2B, 2C, 3B, and 4B are provided to aid in the description of the manner of operation of the various embodiments.

The parts and circuits of this invention are shown diagrammatically and conventional illustrations are used to simplify the drawings and explanations. The drawings have been made to make it easy to understand the principles and manner of operation rather than to show the specific construction and arrangement of parts that would be used in practice. Relays and their contacts are shown in a conventional way. The symbols (+) and (—) indicate connections to the positive and negative terminals, respectively, of a suitable source of direct current preferably of a relatively low voltage. The symbol B+ and the symbol for ground potential indicate connections to the positive and negative terminals, respectively, of another suitable source of direct current preferably of a relatively higher voltage suitable for the electrodes of the various electron tubes employed.

General operation

Briefly, and in a general way, the train-carried apparatus operates to actuate the armature of a two-position code-responsive relay to opposite positions alternately at a rate corresponding to the coding rate of the track current. When operating in regions of direct-current or rectified alternating current track circuit energization, the changeover switch adapts the apparatus to this form of energization by providing a circuit organization substantially as shown in my co-pending application Ser. No. 171,423, filed June 30, 1950; and no claim is intended to be made in this application to any subject matter disclosed in such co-pending application. When operated in this manner, each track code pulse induces a voltage in the receiver coils which are so connected that the voltages induced therein add to each other. The receivers are included in a parallel tuned circuit that is preferably resonant to a relatively low frequency as compared to the usual commercial power frequencies. Oscillations are thus set up by each application and each removal of a track code pulse as is explained in detail in the prior application cited. By properly damping these oscillations, a distinctive voltage output of one polarity is produced at the beginning of each track code pulse and another distinctive voltage output of the opposite polarity is produced corresponding to each removal of a code pulse from the track rails. These distinctive voltages are then amplified and control the operation of the code-responsive relay in such a way that each beginning of a track code pulse actuates the relay armature to one position and each ending of a track code pulse similarly actuates the relay armature to the opposite position.

The code-responsive relay governs the operation of a decoding organization that includes electromagnetic relays selectively responsive according to the code rate of the track current. Various contacts of these relays are then included in circuits that selectively energize the lamps of the cab signal. Thus, the signal aspect displayed in the cab is dependent upon the coding rate. Also, since the coding rate of the track current in any track section is governed by the associated wayside apparatus to correspond to particular traffic conditions in advance of such track section, the cab signal aspect displayed is at all times dependent upon the traffic conditions in existence.

When operating in regions where alternating current track circuit energization is used, the changeover switch is moved to the corresponding position. This action then adapts the circuit so that the receivers are included in a parallel tuned circuit resonant to the frequency of the track current source. Any suitable track current frequency may be employed although a frequency of 100 cycles per second is common and will be assumed to be the frequency of the track current in the description that follows.

The alternating current in the tuned circuit is rectified, preferably by a full-wave, bridge-type rectifier to form a direct-current pulse corresponding to each track current pulse. These resulting direct-current pulses are then acted upon by additional pulse-forming circuit means so that distinctive voltage variations of opposite polarity occur respectively at the beginning and end of each track code pulse. These distinctive voltage variations are amplified and actuate the code-responsive relay alternately to opposite positions at a rate corresponding to the rate of track current coding.

In one embodiment of this invention, the pulse-forming means used to provide the distinctive output voltages in response to the coded alternating track current includes another parallel tuned circuit. This tuned circuit is shock-excited at the beginning and end of each track code pulse by the pulses formed by the rectification of the alternating current pulses induced in the receivers. Each shock excitation initiates an oscillation in the tuned circuit. By properly damping this tuned circuit, distinctive output voltages are formed at the end and beginning of each track code pulse with successive variations of opposite polarity.

In the two other embodiments shown, the pulse forming is accomplished by the charging of condensers through associated resistors. In one form of the invention the rectifier output current is applied directly to the pulse forming means. In the other embodiment the rectifier output pulses are first amplified before being applied to the pulse-forming circuit means.

Track circuit energization

Fig. 1 shows a stretch of track divided into a plurality of track sections and signalled for eastbound traffic as represented by train TN1 by wayside signals 2, 3, and 4. To demonstrate the adaptability of the cab receiving and decoding apparatus to various kinds of track circuit energization, the track sections 1T and 2T have been shown energized by unidirectional current; specifically, direct current is shown applied to the track rails.

In track section 1T, a track battery 15, variable current-limiting resistor 16 and coding contact 17 are connected across the track rails. As coding contact 17 is intermittently actuated by the wayside apparatus 12, each closure of this front contact 17 causes a direct-current pulse to be applied to the rails. The form of the resulting track current is diagrammatically indicated above these track sections in Fig. 1. Similar apparatus is provided to apply coded direct current to the rails of track section 2T. The delay in the rise and decay of track current at the beginnings and ends of the track pulses respectively is caused by the track circuit characteristics including the rail resistance and inductance and the shunt capacitance and conductance and varies therefore with the distance from the feed end as well as with changes in ballast conditions.

The dotted line drawn between the wayside apparatus 12 and the track section ahead denotes that the operation of this wayside apparatus is dependent upon traffic in advance of track section 1T. Similar dotted lines connect the wayside apparatus of blocks 18 and 20 with the track sections in advance.

The circuit providing for the energization of track section 3T includes an alternator 10 connected in series with the primary winding of a transformer T and a coding contact 19 whose operation is governed by the wayside apparatus 20. This wayside apparatus may be of any suitable kind providing for the actuation of contact 19 at a

selective rate corresponding to traffic conditions and also includes apparatus governing the operation of the associated wayside signal 4. The secondary winding of transformer T is connected through variable current-limiting resistor 14 to the rails of track section 3T.

The manually operated selector lever associated with the "Cab receiving and decoding apparatus" of train TN1 must, during the time that this train occupies track sections 1T and 2T, be in the position that conditions the train-operated apparatus for operation with direct track current. Then, as indicated in Fig. 1, the selector lever must be operated to its opposite position as train TN1 enters track section 3T where alternating track current is employed.

As explained, the circuit organization provided for operation with direct track current operates in a manner fully described in my co-pending application Ser. No. 171,423, filed of even date herewith. This co-pending application points out that proper operation of the vehicle-carried apparatus is also obtained when full-wave or halfwave rectified alternating track current is used. Thus, although direct-current track energization is shown in Fig. 1 for track circuits 1T and 2T, rectified alternating current could instead be applied without requiring that the selector lever be operated from the position it is in when direct track current is used.

Operation—Fig. 2A

In the embodiment of the invention shown in Fig. 2A, the selector lever SL and associated relay SR adjust the circuit for operation in either regions of alternating track current or in those regions in which unidirectional track current is employed. When the selector lever SL is in the position shown in Fig. 2A, selector relay SR is de-energized and its back contacts 25, 26, 27, and 28 are closed. The circuit organization thus provided connects condenser 29 in parallel with receivers 30 and 31 which are mounted in inductive relationship to the track rails. The magnitude of condenser 29 is preferably of such a value as to tune the receivers 30 and 31 to a relatively low frequency as compared to the usual power frequencies. In one embodiment, satisfactory operation was obtained by tuning the receivers to approximately 14 cycles per second.

Condenser 29 is shunted by series-connected equal resistors 32 and 33 whose junction is connected to ground. The remaining terminals of resistors 32 and 33 are each connected through a back contact of relay SR and a corresponding grid resistor to the control grid of an electron tube. The upper terminal of resistor 32, for example, is connected through back contact 27 of relay SR and resistor 34 to the control grid of tube 35. The lower terminal of resistor 33 is similarly connected through back contact 28 and resistor 36 to the control grid of tube 37.

The rise and fall of track current occurring at the beginning and end of each direct-current code pulse illustrated in waveform A of Fig. 2B respectively induce voltages in the receivers mounted adjacent the track rails. Each such voltage induced in the receivers starts an oscillation of the tuned circuit with the first half-cycle of the oscillation occurring at the beginning of a code pulse being of opposite polarity to the first half-cycle of the oscillation occurring at the end of a code pulse. When these oscillations are critically damped, only a single voltage variation is retained from each wave train and this single voltage variation corresponds to the first half-cycle of such wave train thus providing an output voltage across the receiver coils such as that shown in waveform B of Fig. 2B. In practice it has been found that the damping may be somewhat less than critical. The advantage gained by less than critical damping is an increased amplitude of the desired voltage variation. A slight voltage variation corresponding to the second half-cycle of the train of waves is retained when the damping is less than critical. Satisfactory operation is still obtained, however,

70 by employing sufficient damping to keep the amplitude 75

of these secondary voltage variations substantially below a level causing relay operation, thereby providing an output voltage across the receivers such as that shown in waveform C of Fig. 2B. As already explained, suitably distinctive output voltages would also be obtained with this circuit organization if rectified alternating track current pulses were applied to the track rails. The detailed explanation concerning the operation of this circuit arrangement provided for use with coded unidirectional track current is included in my co-pending application Ser. No. 171,423, filed of even date herewith.

Tubes 35 and 37 are each preferably provided with class A cathode bias by resistor 38 connected from the cathodes of these tubes to ground. Cathode resistor 38 is by-passed by condenser 39 which is of sufficient size to minimize degenerative effects of the input signal. Since the junction of resistors 32 and 33 is connected directly to ground, and the cathodes of tubes 35 and 37 are also connected through the bias resistor 38 to ground, the voltages appearing on the grids of these tubes are of opposite polarity and each voltage is substantially equal to one-half of the voltage appearing across the parallel tuned circuit because only small voltage drops appear across the grid resistors 34 and 36 and the cathode resistor 38. Thus, the result is that at the beginning of each track code pulse the control grid of either tube 35 or tube 37 is driven less negative at the same time that the control grid of the other tube is driven more negative as illustrated by waveforms D and E of Fig. 2B. At the end of each track code pulse, the control grid of the tube previously made less negative is now driven more negative; whereas, the control grid of the tube previously driven more negative is now driven less negative.

A detailed description of the manner of operation of the balanced amplifiers including tubes 35, 37, 69, and 72 is presented in my co-pending application Ser. No. 171,423, filed of even date herewith, wherein a similar circuit organization is provided for use with unidirectional current track pulses. The full description concerning the manner of operation will, therefore, not be repeated here. Briefly, however, the manner of operation may be summarized as follows: When the grid-cathode voltage of either tube 35 or 37 is made less negative and the grid-cathode voltage of the remaining tube simultaneously more negative at the beginning of a track code pulse, the plate voltage of these tubes decreases and increases respectively. The grid-cathode voltages of the corresponding output amplifier tubes then become more negative and less negative respectively. If, for example, the grid-cathode voltage of tube 35 is made momentarily more negative at the beginning of a code pulse, the plate voltage of this tube will be momentarily increased, thereby also momentarily increasing the grid-cathode voltage of tube 69. At the same time the grid-cathode voltage of tube 37 will be made less negative, resulting in a plate voltage decrease and a corresponding decrease in the grid-cathode voltage of tube 72. Tubes 69 and 72 are both normally cut off because of the fixed bias voltage supplied by battery 75. The fact that the grid-cathode voltage of tube 72 becomes more negative as described cannot affect the conduction of this tube. However, the rise of grid-cathode voltage of tube 69 above cutoff does cause plate current to flow through the upper winding of relay CR, actuating its armature to a corresponding position. At the end of a track code pulse, the conditions are reversed. The grid-cathode voltage of tube 35 is made less negative, thereby momentarily decreasing its plate voltage so as to make the grid-cathode voltage of tube 69 more negative. The grid-cathode voltage of tube 37 is made more negative, however, thereby increasing its plate voltage and the grid-cathode voltage of tube 72. This time, therefore, tube 69 remains cut off, but tube 72 now conducts plate current through the lower winding of relay CR to actuate this relay to the opposite position. Thus, relay CR is

actuated to opposite positions upon successive beginnings and ends of the code pulses in the track rails. The decoding apparatus, shown in Fig. 4A, distinctively responds to the rate of actuation of relay CR and causes the proper cab signal aspect to be displayed.

As shown in Fig. 2A, a series trap circuit is between the plate of each of tubes 35 and 37 and the source of plate potential. Although these trap circuits are primarily included for use when the apparatus is used in areas of rectified alternating track currents, they may be highly useful in preventing interfering alternating currents of any frequency from adversely affecting the operation of the train-carried apparatus. A detailed explanation concerning one application of these trap circuits is presented in my co-pending application Ser. No. 171,423, filed of even date herewith.

Resistors 34 and 36 are included to prevent improper operation of the circuit under certain conditions of malfunctioning of the apparatus. If, for example, an intermittent short circuit were to occur between the control grid and plate electrodes of tube 35, the direct voltage then applied to the parallel tuned circuit would initiate transient oscillations. The removal of the direct voltage would also initiate these oscillations. These oscillations might then be amplified and cause false operation of the code-responsive relay CR. This possibility of erroneous operation is prevented by the inclusion of grid resistors 34 and 36. These resistors present a relatively high resistance to the direct voltage as compared to the resistance presented by the parallel tuned circuit. Thus, during a short circuit between control grid and plate of tube 35, most of this direct voltage appears across resistor 34, and the amount of this voltage appearing across the parallel tuned circuit is then of insufficient amplitude to produce transient oscillations of great enough magnitude to cause operation of relay CR.

When the selector lever SL is operated to its dotted line position, a circuit is completed to energize the selector relay SR. With front contacts 25 and 26 of this relay closed, a condenser 45 and a rectifier 46 preferably of the kind providing full-wave rectification are connected in series across receivers 30 and 31. This condenser is chosen to be of the proper size to tune the receivers to the track current frequency which is assumed in this description to be 100 cycles per second.

The circulating current in the tuned circuit including receivers 30 and 31 and condenser 45 caused by the coded track current illustrated in waveform A of Fig. 2C is rectified by full wave rectifier 46. The resulting rectifier output includes sine loops on successive half-cycles as shown in waveform B. This output of rectifier 46 is applied to the primary winding of a transformer T1. The secondary winding of transformer T1 has connected across it a condenser 47, thereby providing a tuned circuit having a natural frequency relatively low as compared to the usual power frequencies. For purposes of analysis, to obtain a possible theory of operation concerning this embodiment of the invention, this output of the rectifier may be considered as comprising a direct-current component plus a number of alternating-current components. Although the response of the tuned circuit comprising the secondary winding of transformer T1 and condenser 47 is actually caused by the composite current in the tracks as shown in waveform B, the response of the circuit organization may be considered as being the sum of the various responses produced by the corresponding components included in the rectifier output.

The predominant components in the full wave rectifier output are a direct-current component and, if the track current is at 100 cycles per second, an alternating-current component of 200 cycles per second. Various other components at 400 and 800 cycles and still other higher frequency harmonics also appear but the amplitudes of these higher harmonics become progressively smaller so that their effect is correspondingly small.

During the time that the direct-current component is steadily applied to the transformer primary winding, no effect is produced in the secondary winding because there is then no change of flux in the primary winding. Only at the beginning and end of each track pulse when the direct-current component respectively increases and decreases is there a voltage induced in the secondary winding as a result of the direct-current component. Because the values of the components included in the secondary tuned circuit are so chosen as to make this circuit oscillatory, transient oscillations are initiated in the tuned circuit each time that a voltage is induced in the secondary winding as a result of the direct-current component. These oscillations occur at a rate corresponding to the natural period of oscillation of the tuned circuit.

The predominant alternating-current component present during the time of each code pulse in the tracks produces a continually varying flux in the primary winding, thereby inducing a corresponding voltage in the secondary winding. The rapid change of the direct-current component at the beginning and end of each code pulse produces the transient oscillations already described. Therefore, the composite receiver output voltage occurring during the "on" period of the code when the trap circuit including condenser 49 and inductance 50 and also resistors 65 and 66 are removed includes the relatively high frequency alternating-current variations with the average value thereof varied according to the transient produced by the direct-current component as is shown in waveform C of Fig. 2C. Since the predominant rectifier ripple component is of a frequency twice that of the track current frequency, the main alternating component of the receiver output is also of this frequency and its average value varies in a sinusoidal appearing manner with the rate of variation of average value corresponding to the frequency of the oscillations occurring as a result of the direct-current component that shock excites the tuned circuit. The amplitude of successive variations of the average value is attenuated because of the resistance inherently present in the tuned circuit.

At the end of each track code pulse, the rapid decay of the direct-current component again causes oscillations in the tuned circuit. These oscillations, however, are free of the higher frequency ripple because the alternating-current component that produces the ripple during the "on" period of the code is not present during the code "off" period. The oscillations during the "off" period are also attenuated by the resistance inherently present in the tuned circuit. The first half-cycle of oscillation of the average value occurring at the end of each track code pulse and subsequent half cycles as well are of the opposite polarity as compared with corresponding half cycles of the oscillations initiated at the beginning of each track code pulse as is shown in waveform C.

A waveform of voltage across the secondary tuned circuit having substantially the form shown in waveform C of Fig. 2C does not provide a completely suitable input for the amplifying organization controlling the code-responsive relay CR. The waveform of this voltage is considerably improved, however, by adding damping resistors 65 and 66 shown in Fig. 2A. If resistors 65 and 66 are chosen to be of such a value that critical damping of the oscillations is obtained, only a single variation of the average value is retained at the beginning of each code pulse and another single variation of opposite polarity at the end of each code pulse. The distinctive voltage variations thus obtained to indicate the beginning and end of each track code pulse correspond to the first half-cycles of the trains of oscillations set up respectively at the beginning and ends of the track pulses and may, under certain conditions, be energizing the balanced amplifier organization to control relay CR. Experiments show that the damping provided by resistors 65 and 66 may be less than that amount of damping known as critical damping, thereby retaining to a small degree the

second half-cycle of each train of oscillations and providing an output voltage similar to that shown in waveform D. If the damping is just less than critical, this second half cycle will not be of sufficient amplitude to obtain false response of relay CR but the advantage gained is a greater amplitude of the first half-cycle thus insuring proper operation of the apparatus with lower values of track current. Thus, in one embodiment, resistors 65 and 66 were chosen to be of twice the value required for critical damping thereby obtaining satisfactorily distinctive voltage outputs to denote the beginning and end of each code pulse.

The ripple present in the voltage across the tuned circuit when the trap circuit is omitted is of sufficient amplitude as shown in waveform D that it will, upon amplification, cause a chattering of the relay CR. To prevent this condition, resistor 48, condenser 49, and inductance 50 are included as a trap circuit. Condenser 49 and inductance 50 are chosen to be series-resonant at the frequency of the ripple voltage. If, for example, the frequency of the track current is 100 cycles per second, the most important component of this ripple will have a frequency of 200 cycles per second because of the full-wave rectification employed and the series-resonant circuit will then be tuned to this latter frequency. Consequently, this resonant circuit presents a very low impedance to the 200 cycle ripple voltage, but presents a very high impedance to other frequencies. At the 200 cycle frequency, the impedance of the resonant circuit is small as compared to the magnitude of the resistor 48 and, therefore, only a negligible amount of the ripple voltage is applied through front contacts 27 and 28 and grid resistors 34 and 36 to the control grids of tubes 35 and 37, respectively. At other frequencies such as the 14 cycle resonant frequency of the parallel tuned circuit the series-resonant circuit presents a high impedance as compared to the magnitude of resistance of resistor 48. Therefore, substantially all of the desired signal voltage appearing across the parallel tuned circuit appears between the control grids of tubes 35 and 37.

The resulting waveform of voltage then produced by the secondary tuned circuit cooperating with the trap circuit and damping resistors 65 and 66 not only provides suitably distinctive output voltages to indicate the beginning and end of each code pulse but also contains but a small percentage of ripple as shown in waveform E of Fig. 2C. To summarize, the operation of this circuit organization is such that a voltage variation of one polarity appears across series-connected resistors 65 and 66 at the beginning of each track code pulse, and another voltage variation of opposite polarity occurs at the end of each track code pulse.

Since the junction of damping resistors 65 and 66 is connected through common cathode resistor 33 to the cathodes of both tubes 35 and 37, the grid-cathode voltages of tubes 35 and 37 are of opposite polarity. Also, grid resistors 34 and 36 and cathode resistor 38 shunted by condenser 39 present a relatively low impedance to the input signal as compared to the impedance presented across the source of the input signal as measured between front contacts 27 and 28 for example. Therefore, the grid-cathode voltages of tubes 35 and 37 are substantially equal to the signal voltages appearing across resistors 65 and 66 respectively. Because resistors 65 and 66 are of equal magnitude, the grid-cathode voltages of tubes 35 and 37, although of opposite polarity, have substantially equal amplitudes.

Resistors 34 and 36 are included in series with the control grids of tubes 35 and 37 respectively regardless of whether relay SR is energized or deenergized. When the apparatus is adapted for operation in response to alternating-current track pulses, these resistors fill the same requirement as that explained in connection with operation of the apparatus with direct-current or rectified alternating-current track pulses; in brief, they prevent

improper responses of the input circuit in the event of intermittent short circuits between plate and grid of either tube 35 or 37.

At the beginning of each track code pulse, the grid-cathode voltage of either tube 35 or 37 is made less negative at the same time that the grid-cathode voltage of the other tube is made more negative. Since, as already mentioned, tubes 35 and 37 are preferably provided with class A self bias, these tubes may conduct more and less plate current as their grid-cathode voltages respectively are made less negative and more negative. Assume, for example, that tube 35 conducts more current and tube 37 less at the beginning of a track code pulse. The momentary increase of tube 35 plate current through load resistor 67 then causes a corresponding momentary decrease of the plate voltage of this tube. The negative-going voltage variation thus produced on the plate of tube 35 is applied through coupling condenser 68 to the control grid of tube 69. At the same time, tube 37 conducts less plate current thereby producing a corresponding increase of its plate potential because of decreased current through load resistor 70. Consequently, a positive-going voltage variation is then applied through coupling condenser 71 to the control grid of tube 72.

The control grids of tubes 69 and 72 are connected through the associated grid-leak resistors 73 and 74, respectively, to the negative terminal of a source of bias potential denoted by battery 75. Tubes 69 and 72 are preferably of the sharp cutoff variety and the bias applied to their control grids by battery 75 is sufficient normally to cut off the plate current of these tubes. The cathodes of tubes 69 and 72 are both connected to ground. The plates of tubes 69 and 72 are each connected through a corresponding winding of polar relay CR to a source of positive potential designated B+.

Under the assumed set of connections, the grid-cathode potential of tube 69 is decreased at the beginning of a track code pulse, and the grid-cathode potential of tube 72 is simultaneously increased. The decrease of tube 69 grid potential can have no effect upon the conduction of this tube since it is already cut off. The increase of grid voltage of tube 72, however, now permits this tube to conduct and the resulting plate current through the lower winding of relay CR then actuates this relay to a corresponding position.

Under the same assumed conditions, the end of a track code pulse causes tube 35 to conduct less plate current and tube 37 to conduct more plate current. Therefore, the plate voltage of tube 35 will rise at the same time that the plate voltage of tube 37 decreases. A corresponding increase of voltage then appears on the grid of tube 69 and a decrease of grid-cathode voltage of tube 72. This time the conduction of tube 72 is unaffected, but with the grid-cathode voltage of tube 69 raised above cutoff, this tube now conducts and the resulting plate current through the upper winding of relay CR now actuates this relay to the opposite position. As a result, relay CR is actuated first to one position and then to the other at a rate corresponding to the rate at which code pulses are applied to the track rails. As indicated in Fig. 2A, the decoding apparatus associated with the contacts of relay CR may be of the form shown in Fig. 4A and described in connection with that drawing.

Operation—Fig. 3A

In the embodiment of the cab receiving and decoding apparatus shown in Fig. 3A, the position of selector lever SL determines whether the circuit organization is adapted to operation with alternating-current track circuits or with unidirectional current track circuits. When the selector lever SL is in the position shown in Fig. 3A, relay SR is deenergized and its back contacts 76, 77, 78, and 79 closed. The circuit organization thus provided connects condenser 80 across the series-connected receivers 81 and 82 mounted adjacent the track rails, thereby tun-

ing these receivers to a relatively low frequency with respect to the usual commercial power frequencies. The remainder of the circuit organization thus provided by the dropping away of relay SR for operation with direct-current track pulses is the same as is shown in Fig. 2A. A trap circuit including condenser 96 and inductance 97 is connected between the plate of tube 102 and B+. A similar trap circuit including condenser 98 and inductance 99 is connected between the plate of tube 103 and B+. These trap circuits fulfill the same requirement as do the corresponding trap circuits explained in connection with Fig. 2A. The manner of operation of this form of the invention in response to direct track current is the same as that of the similar circuit organization of Fig. 2A as it operates in response to direct-current track pulses in that distinctive voltage variations are provided at the beginning and end of each track code pulse with successive voltage variations of opposite polarity. These voltage variations are then amplified as was explained in connection with Fig. 2A and cause the code-responsive relay CR to be actuated alternately to opposite positions at a rate corresponding to the coding rate of the track current.

When the selector lever SL is operated to the dotted line position, relay SR is energized and closes its front contacts 76, 77, 78, and 79. Condenser 85 and full-wave rectifier 86 are then connected in series across the series-connected receivers 81 and 82. Condenser 85 is preferably of the size required to tune the receivers to a frequency equal to the frequency of the alternating track current which has been assumed to be of 100 cycles per second and is diagrammatically illustrated by waveform A in Fig. 3B. The 200 cycle ripple component of the rectifier output is filtered by condenser 87, and resistors 88 and 89 connected across the rectifier output terminals, thereby providing a voltage across condenser 87 having ripple superimposed upon the direct-current component as shown in waveform B.

In this form of the invention, no loose inductive coupling is provided as in the embodiment shown in Fig. 2A to reduce the load on rectifier 86. A steady load appears across the rectifier output terminals by reason of the current drawn by resistors 88 and 89. This relatively heavy load on the rectifier output has the effect of reducing the selectivity of the tuned circuit including the receivers 81 and 82 and condenser 85. To prevent stray interfering track currents of frequencies other than that of the coded track current from being amplified by the cab apparatus, condenser 90 and inductance 91 are connected in series across the input terminals of rectifier 86. Condenser 90 and inductance 91 are preferably tuned to series resonance at a frequency equal to that of the predominating interference. Thus, in regions where power lines are located along the right-of-way distributing 60 cycle power, this trap circuit including condenser 90 and inductance 91 would preferably be tuned to this 60 cycle frequency to present a low impedance path for currents of this frequency thereby preventing their appearance, to a substantial degree, in the rectifier output.

To provide distinctive voltage variations at the beginning and end of each track code pulse, pulse-forming circuit means including resistors 88, 89, 92 and 93, and condensers 94 and 95 are provided. This pulse-forming circuit may be said to operate on the principle of a differentiating circuit as will be explained.

The directions of the arrows associated with the full-wave rectifier 86 indicates that the voltage at point 109 is made positive with respect to voltage of point 101 as a result of each track code pulse. During the "off" period of the track code prior to any "on" period, any charges previously placed across condensers 94 and 95 reduce to zero because of the discharge path of these condensers provided by resistors 88, 89, 92, and 93. As the voltage of point 109 is suddenly made positive with respect to that at point 101 at the beginning of a track code pulse, charging current for condensers 94 and 95 passes through

resistors 92 and 93 in such a direction as to make the voltage at the junction of condenser 94 and resistor 92 positive with respect to the junction of resistors 92 and 93. At the same time the voltage at the junction of condenser 95 and resistor 93 becomes negative with respect to the junction of resistors 92 and 93. Thus, the grid-cathode voltage of tube 102 is suddenly made less negative as compared to its normal cathode bias voltage at the same time that the grid-cathode voltage of tube 103 is made more negative. The charging current for condensers 94 and 95 is at first maximum but decreases as the voltage across each of these condensers increases. Therefore, the relatively sudden increase in average value of the voltage across resistors 92 and 93 at the beginning of each track pulse is followed by a decrease of voltage with the rate of the decrease being dependent upon the time constant of condensers 94 and 95 associated with resistors 92 and 93. A short time constant produces a relatively narrow voltage variation; whereas a long time constant brings about a corresponding increase in the duration of the voltage variation.

At the end of each track code pulse another voltage variation of opposite polarity is produced. These voltage variations occurring as a result of the removal of track current are free from the distinctive ripple caused by the alternating current because the alternating track current is, of course, not present in the rails at that time. In summary then, the voltage across resistors 92 and 93 as shown in waveform C includes a distinctive voltage variation at the beginning of each track code pulse and another distinctive voltage variation of opposite polarity at the end of every code pulse.

Tubes 102 and 103 of Fig. 3A are provided with class "A" bias by means of cathode resistor 104 which is bypassed by condenser 105. Grid resistors 106 and 107 are here also provided to prevent spurious responses of the input circuit as explained in connection with Fig. 2A in the event that intermittent short circuit should occur between grid and plate of either tube 102 and 103. The remainder of the circuit shown in Fig. 3A operates in the same manner as that shown in Fig. 2A. Connecting the cathodes of both tubes 102 and 103 through resistor 104 and condenser 105 to the junction of equal resistors 92 and 93 causes the grid-cathode voltages of these tubes to be equal and of opposite polarity. Thus, as the grid-cathode voltage of tube 102 is momentarily made less negative, the grid-cathode voltage of the associated tube 103 is momentarily driven more negative. The subsequently occurring input to these tubes reverses the situation with the grid of tube 102 being driven momentarily more negative at the same time that the grid of tube 103 becomes less negative. Each time that the grid voltage of either tube 102 or 103 is made less negative, its plate voltage decreases because of the increase of plate current through resistor 115. As the grid voltage of either tube becomes more negative, its plate voltage increases because of its decrease of plate current.

Tubes 116 and 117 are both biased to cutoff by reason of their grids being connected through resistors 118 and 119, respectively, to the negative terminal of a source of bias voltage 120. Therefore, a decrease of voltage, for example, applied from the plate of tube 102 through coupling condenser 108 to the grid of tube 116 cannot affect the conduction of this tube. However, the simultaneously occurring increase of tube 103 plate voltage through coupling condenser 109 to the grid of tube 117 increases the grid voltage of this tube 117 so that it conducts plate current through the lower winding of relay CR. The armature of relay CR is then actuated to a corresponding position. The next input applied to tubes 102 and 103 causes a decrease in tube 103 plate voltage and an increase in tube 102 plate voltage which then causes a corresponding increase of tube 116 grid voltage. Tube 116 then conducts plate current through the upper winding of relay CR and the armature of this relay is then actuated to the

opposite position. In this way, relay CR is alternately actuated to one position and then to the other at a rate corresponding to the coding rate of the track current. This embodiment shown in Fig. 3A ordinarily has associated therewith decoding apparatus which may be of the form shown in Fig. 4A and has, therefore, only been indicated diagrammatically in Fig. 3A. The function of such decoding apparatus is, of course, to control the cab signal so that it will display the proper signal aspect according to the rate of actuation of relay CR and in turn, therefore, according to the existing traffic conditions.

Operation—Fig. 4A

A third embodiment of the cab receiving and decoding apparatus is shown in Fig. 4A. The manner of operation of this circuit organization is in general somewhat similar to that shown in Fig. 3A. A major point of difference, however, is that the output of the rectifier is applied after filtering directly to the control grids of the first stage of amplification. The pulse-forming means is included between the plates of the tubes included in this first stage and the control grids of the tubes included in the second stage of amplification.

With the selector lever SL in the position shown so that relay SR is deenergized, back contacts 125 and 126 of this relay are closed and front contact 127 is open. The series-connected receivers 128 and 129 thus have connected across them condenser 130 which provides a parallel tuned circuit resonant to a relatively low frequency such as 14 cycles per second. The beginning and end of each track code pulse, regardless of whether the track current consists of direct current or rectified alternating current, produces oscillations of the tuned circuit. These oscillations are then suitably damped by resistors 131 and 132 connected in series across condenser 130. These resistors are preferably of such a value that the damping produced is slightly less than that amount of damping which is ordinarily termed critical damping. The manner of operation for operation with direct-current or rectified alternating-current track pulses is thus the same as that explained in detail in connection with Fig. 2A. Condenser 130 and resistors 131 and 132 shown in Fig. 4A perform the same function as that performed by condenser 29 and resistors 32 and 33, respectively, shown in Fig. 2A.

As in the two previous forms of the invention shown in Figs. 2A and 3A, grid resistors 133 and 134 are included in series with the control grids of tubes 135 and 136, respectively. These resistors are here also included to prevent undesirable oscillations of the tuned circuit in the event of intermittent short circuit between the plate and control grid of either tubes 135 and 136. A trap circuit is included between the plate and the B+ source of each of the tubes 135 and 136. The trap circuit connected between the plate of the tube 135 and B+ includes condenser 137 and inductance 138. Similarly, the trap circuit connected between the plate of tube 136 and B+ includes condenser 139 and inductance 140. These trap circuits perform the same functions as the corresponding trap circuits already mentioned in connection with Figs. 2A and 3A.

When the selector lever SL is moved to the dotted line position, so that relay SR becomes energized, front contacts 125, 126, and 127 are closed thereby connecting condenser 145 and full wave rectifier 146 in series across the receivers 128 and 129. As in the embodiment shown in Fig. 3, a trap circuit including condenser 147 and inductance 148 is connected across the input terminals of rectifier 146 and is similarly used to aid in the rejection of interfering frequencies. By tuning this trap circuit to resonance at the frequency of the interfering currents, these currents are prevented from being applied to the input of the rectifier because of the low impedance shunt path provided for them through the trap circuit. The rectifier output thus includes a direct-current component and also some ripple voltage having its main component at

a frequency twice that of the track current because of the full-wave rectification as is shown in waveform B of Fig. 4B. Condenser 130 connected across the output of the rectifier acts now as a filter condenser and thereby reduces the ripple amplitude of the rectifier output.

In this embodiment of the invention the pulse-forming means includes resistors 155, 156, 161, and 162 and also condensers 157 and 159. The manner of operation of this circuit organization is in general similar to that of the corresponding circuit means included in Fig. 3A.

Tubes 135 and 136 are provided with class A bias by cathode resistor 149 which is by-passed by condenser 150. Since the cathodes of both tubes 135 and 136 are connected through resistor 149 to the junction of the resistors 131 and 132, the grid-cathode voltages of tubes 135 and 136 are of opposite polarity. Also, since resistors 133, 134, and 149 are of relatively low resistance, substantially all of the input voltages appearing across resistors 131 and 132 also appear between the grid and cathode of the corresponding tubes 135 and 136.

Because resistors 131 and 132 are connected in series across the rectifier output, the input voltages to tubes 135 and 136 each appear similar in form to that of the rectifier output shown in waveform B except that the grid-cathode voltages of these tubes are of opposite polarity. The similarly appearing output voltages appear across the respective load resistors 155 and 156. Assuming a particular set of connections, the grid-cathode voltage of tube 135 suddenly is driven more negative at the beginning of a code pulse so that the plate voltage of this tube increases. Because the voltage across condenser 157 cannot instantly be changed, this increase in plate voltage of tube 135 produces a corresponding increase in the grid-cathode voltage of tube 138. The grid-cathode voltage of tube 136 is at the same time increased so that the plate voltage of this tube decreases. The voltage across condenser 159 similarly cannot suddenly be changed so that a corresponding decrease in potential occurs between grid and cathode of tube 160. Following the sudden changes in potential at the plates of tubes 135 and 136, condensers 157 and 159 charge through resistors 161 and 162, respectively. As these condensers become charged, the charging rate decreases exponentially thereby reducing the magnitudes of the voltage variations produced on the control grids of tubes 138 and 160. Consequently, during each "on" period of the track code the grid-cathode voltage of these output tubes 138 or 160 includes the ripple components continually present during each such "on" period but with its average value rising abruptly at the beginning of the code pulse and then decaying again towards zero as illustrated in waveform C. At the end of each track code pulse, a similar appearing voltage variation of opposite polarity is produced but without, of course, the ripple components because the track current is nonexistent at that time.

Because the control grids of tubes 138 and 160 are connected through equal resistors 161 and 162, respectively, and through battery 163 to ground, and because the cathodes of tubes 138 and 160 are both connected to ground the grid-cathode voltages of these tubes are not only of substantially equal magnitude, but also of opposite polarity. Thus, if the grid-cathode voltage of tube 138 is suddenly driven less negative, for example, the grid-cathode voltage of tube 160 is simultaneously driven more negative by substantially the same amount.

Tubes 138 and 160 are both biased to cutoff because of the connections of their control grids through resistors 161 and 162 to the negative terminal of a source of bias voltage 163. If, through a particular set of connections, the grid-cathode voltage of tube 138 becomes less negative at the beginning of a track code pulse so that the grid voltage of this tube might be represented by waveform C of Fig. 4B, then tube 138 conducts at the beginning of each track code pulse as its control grid is driven less negative. The upper winding of relay CR is thus ener-

gized and its armature actuated to a corresponding position. At the end of each track code pulse, the conduction of this tube is not affected since the driving of its control grid negatively below the quiescent cutoff point cannot change the conduction of this tube. The voltage applied to the control grid of tube 160, on the other hand, is of the opposite polarity to the voltage applied to the grid of tube 138. The conduction of tube 160 is, therefore, not affected by the beginning of a track code pulse when its grid-cathode voltage is driven negatively beyond cutoff, but this tube does conduct at the end of each track code pulse when its grid is driven in the positive direction. The lower winding of relay CR is then energized and the relay armature actuated to the opposite position. The armature of this relay will thus be actuated to one position and then the other at a rate determined by the coding rate of the track current. Consequently, the decoding apparatus, such as that associated with the contacts of relay CR, is actuated and causes the proper cab signal to be displayed.

In this form of the invention shown in Fig. 4A, capacitors 157 and 159 perform two functions. When lever SL is moved to the "D. C." position, the plate outputs of tubes 135 and 136 comprise the distinctive output voltages produced as a result of the shock excitation of a tuned circuit. Capacitors 157 and 159 should then preferably be relatively large to present a low value of impedance to the pulsing output of tubes 135 and 136 so that most of the voltage drop will occur across the respective grid leak resistors 161 and 162 and thus be as useful grid-cathode driving voltage of tubes 138 and 160. However, when lever SL is moved to the "A. C." position for operation with alternating track current, the plate output of tubes 135 and 136 comprises pulses having a duration substantially equal to that of an "on" period of the track code. To provide distinctive output voltages in response to these output pulses of tubes 135 and 136, condensers 157 and 159 must be relatively small so that they may become fully charged within a relatively short time following the beginning and end of each track code pulse. Despite these seemingly divergent requirements, in practice a satisfactory value for capacitors 157 and 159 has been found by experimentation to give the desired results for either alternating or unidirectional track current.

Decoding apparatus

Each time that code receiving relay CR included in each embodiment of the invention is actuated to close its front contacts 170 and 171 (see Fig. 4A), front repeater relay CRFP is energized through a circuit including these contacts 170 and 171. If relay CR is actuated to its alternate positions at a rate corresponding to that at which direct-current pulses are applied to the track rails, front repeater relay CRFP will remain steadily picked up despite its intermittent energization because of its slow releasing characteristics. Front contacts 172 and 173 of relay CRFP will then be closed. Therefore, each closure of back contacts 170 and 171 of relay CR will energize back repeater relay CRBP. Since this relay is also provided with slow releasing characteristics, relay CRBP will also remain picked up despite its intermittent energization. This arrangement of front and back repeater relays of the code receiving relay CR ensures, by the picking up of relay CRBP, that relay CR is actually energized to opposite positions in response to the code pulses appearing on the track relays and is not steadily held in one position.

Contact 174 of relay CR, together with transformer 175, condenser 176, transformer 177, and rectifier 178 provide a decoding circuit that enables relay 180R to be picked up whenever relay CR is energized at the 180 rate. The form of decoding circuit shown in Fig. 4A is typical of that generally employed in coded track circuit signalling systems. Briefly, each time that contact 174 of relay CR is energized to one position or the other, one-half of the primary winding of transformer 175 is

energized through a circuit including this contact 174 and also front contact 179 of back repeater relay CRBP. The secondary winding of transformer 175 is shunted by a series resonant circuit including condenser 176 and the primary winding of transformer 177. This series resonant circuit is tuned to 180 cycles per minute with the result that the secondary winding of transformer 177 is energized only when the primary winding of transformer 175 is energized at the 180 rate. The alternating voltage appearing across the secondary winding of transformer 177 is then rectified by full wave rectifier 178 so that relay 180R is energized with direct current. If relay CR is not intermittently actuated to opposite positions in the 180 rate in response to a 180 code applied to the track rails, relay 180R will not be energized.

When relay CR is energized in response to a 180 code, both front contacts 180 of relay CRBP and 181 of relay 180R are closed. Lamp 182 of the cab signal is then energized to display a green aspect. If relay CR is energized at the 75 rate, however, relay CRBP is still energized but relay 180R is dropped away. In that event, lamp 183 of the cab signal is then energized through front contact 180 of relay CRBP and back contact 181 of relay 180R. A yellow aspect is then displayed by the cab signal. If the contacts of relay CR remain steadily in one position or the other, both relays CRBP and 180R are deenergized. A circuit is then completed through back contact 180 of relay CRBP and back contact 184 of relay 180R to energize lamp 185 of the cab signal. A red aspect is then displayed by the cab signal.

By means of the circuit organization shown in Fig. 4A a cab signal may be selectively energized to display a proper signal aspect dependent upon the rate at which the CR relay is energized. Although the 180 and 75 rates have been chosen as indicative of clear and caution signal conditions, other code rates may, of course, be used as desired. By using additional code rates, a larger number of different signal aspects may be displayed by the cab signal.

The cab signalling system thus provided by this invention permits proper operation of the train-carried apparatus with various kinds of track circuit energization. In addition, the circuit organization is so devised as to prevent an improper signal aspect from being displayed under various conditions of failure of the apparatus. For example, as already explained, the resistors connected in series with the control grids of the two tubes in the first stage of amplification prevent oscillations in the input tuned circuit in the event of an intermittent short circuit between the grid and plate of either of these tubes. Furthermore, the use of two channels of amplification with each channel controlling the energization of a corresponding winding of relay CR also contributes to the safety of this system. More specifically, any intermitting occurring circuit fault affecting both tubes of the first amplifier stage simultaneously cannot cause relay operation. Thus, if the common cathode connection of the two tubes in the first amplifier stage is intermittently opened, the plate voltages of these tubes rises simultaneously. The grid-cathode voltages of both tubes in the second amplifier stage would then both become less negative simultaneously causing both tubes to conduct plate current through their respective relay windings. When both relay windings are simultaneously energized, the code-responsive relay CR cannot be picked up.

The trap circuits included between the plate of each of the input amplifier tubes and B+ have been described as primarily preventing improper operation in the event that the apparatus is used in regions where rectified alternating currents are used to energize the track circuits. These trap circuits may, under certain circumstances, also be highly useful when the apparatus is used in regions of either direct-current or alternating-current track energization. Thus, if the direct current for the track circuits is obtained by rectification of alternating current

instead of by a battery as is shown in Fig. 1, the trap circuits will then properly tuned, prevent the ripple of the direct current pulses from causing chatter of the relay. Also, when operated in regions of either direct or alternating-current track circuit energization, these trap circuits may aid in preventing stray currents in the rails as from commercial power lines from adversely affecting the operation of the apparatus.

Having described three forms of code detecting and decoding apparatus for use with a cab signalling system as specific embodiments of the present invention these forms have been selected to facilitate the disclosure of the invention rather than to limit the number of forms which it may assume. Furthermore, various modifications, adaptations, and alterations may be applied to the specific forms shown to meet the requirements of practice without in any manner departing from the spirit or scope of the present invention.

What I claim is:

- 20 1. In a cab signalling system for railroads, a plurality of track sections with means for applying pulses of unidirectional current to the rails of certain of said track sections and additional means for applying pulses of alternating current to the rails of other of said track sections, vehicle-carried apparatus including receiver coils positioned adjacent the rails of said track section, first circuit means including a condenser to tune said receiver coils to a relatively low frequency as compared to the usual power frequencies and damping means for damping the electrical oscillations in said receiver coils to provide distinctive output voltages of opposite polarity corresponding respectively to the beginning and end of each unidirectional track current pulse, second circuit means including a condenser to tune said receiver coils to the frequency 25 of said alternating current and also including means for providing distinctive output voltages of opposite polarity corresponding respectively to the beginning and end of each alternating track current pulse, manually operable selector means for associating either said first or said second circuit means with said receiver coils, circuit means including electron discharge tubes for amplifying the distinctive output voltages provided by either said first or said second circuit means, relay means including a two-position relay operable to either of its two different positions and actuated alternately to its opposite positions in response to said distinctive voltages, and decoding means governed by said relay means and selectively operated according to the rate of coding of either said unidirectional or said alternating track current.
- 30 2. A cab signalling system for railroads comprising, a plurality of track sections with means for applying pulses of unidirectional current to the rails of certain of said track sections and additional means for applying pulses of alternating current to the rails of other of said track sections, said current pulses being applied to said rails at selected rates according to traffic conditions, vehicle-carried apparatus including receiver coils positioned adjacent the rails of said track sections, first pulse-forming circuit means including first tuning and damping resistance means responsive to said unidirectional track current for producing distinctive pulses of opposite polarity corresponding respectively to the beginning and end of each track code pulse, second pulse-forming means including second tuning and damping resistance means responsive to said alternating track current also for producing a distinctive output voltage of one polarity at the beginning of each track code pulse and another distinctive output voltage of opposite polarity at the end of each track code pulse, circuit means including electron discharge tubes, selector means for connecting either said first or said second pulse-forming means between said receiver coils and said circuit means including said electron tubes, relay means including a two-position relay operable to either of its two different positions and operated alternately to its opposite positions in response to said distinctive voltages,
- 35 3. A cab signalling system for railroads comprising, a plurality of track sections with means for applying pulses of unidirectional current to the rails of certain of said track sections and additional means for applying pulses of alternating current to the rails of other of said track sections, said current pulses being applied to said rails at selected rates according to traffic conditions, vehicle-carried apparatus including receiver coils positioned adjacent the rails of said track sections, first pulse-forming circuit means including first tuning and damping resistance means responsive to said unidirectional track current for producing distinctive pulses of opposite polarity corresponding respectively to the beginning and end of each track code pulse, second pulse-forming means including second tuning and damping resistance means responsive to said alternating track current also for producing a distinctive output voltage of one polarity at the beginning of each track code pulse and another distinctive output voltage of opposite polarity at the end of each track code pulse, circuit means including electron discharge tubes, selector means for connecting either said first or said second pulse-forming means between said receiver coils and said circuit means including said electron tubes, relay means including a two-position relay operable to either of its two different positions and operated alternately to its opposite positions in response to said distinctive voltages,
- 40 4. A cab signalling system for railroads comprising, a plurality of track sections with means for applying pulses of unidirectional current to the rails of certain of said track sections and additional means for applying pulses of alternating current to the rails of other of said track sections, said current pulses being applied to said rails at selected rates according to traffic conditions, vehicle-carried apparatus including receiver coils positioned adjacent the rails of said track sections, first pulse-forming circuit means including first tuning and damping resistance means responsive to said unidirectional track current for producing distinctive pulses of opposite polarity corresponding respectively to the beginning and end of each track code pulse, second pulse-forming means including second tuning and damping resistance means responsive to said alternating track current also for producing a distinctive output voltage of one polarity at the beginning of each track code pulse and another distinctive output voltage of opposite polarity at the end of each track code pulse, circuit means including electron discharge tubes, selector means for connecting either said first or said second pulse-forming means between said receiver coils and said circuit means including said electron tubes, relay means including a two-position relay operable to either of its two different positions and operated alternately to its opposite positions in response to said distinctive voltages,
- 45 5. A cab signalling system for railroads comprising, a plurality of track sections with means for applying pulses of unidirectional current to the rails of certain of said track sections and additional means for applying pulses of alternating current to the rails of other of said track sections, said current pulses being applied to said rails at selected rates according to traffic conditions, vehicle-carried apparatus including receiver coils positioned adjacent the rails of said track sections, first pulse-forming circuit means including first tuning and damping resistance means responsive to said unidirectional track current for producing distinctive pulses of opposite polarity corresponding respectively to the beginning and end of each track code pulse, second pulse-forming means including second tuning and damping resistance means responsive to said alternating track current also for producing a distinctive output voltage of one polarity at the beginning of each track code pulse and another distinctive output voltage of opposite polarity at the end of each track code pulse, circuit means including electron discharge tubes, selector means for connecting either said first or said second pulse-forming means between said receiver coils and said circuit means including said electron tubes, relay means including a two-position relay operable to either of its two different positions and operated alternately to its opposite positions in response to said distinctive voltages,
- 50 6. A cab signalling system for railroads comprising, a plurality of track sections with means for applying pulses of unidirectional current to the rails of certain of said track sections and additional means for applying pulses of alternating current to the rails of other of said track sections, said current pulses being applied to said rails at selected rates according to traffic conditions, vehicle-carried apparatus including receiver coils positioned adjacent the rails of said track sections, first pulse-forming circuit means including first tuning and damping resistance means responsive to said unidirectional track current for producing distinctive pulses of opposite polarity corresponding respectively to the beginning and end of each track code pulse, second pulse-forming means including second tuning and damping resistance means responsive to said alternating track current also for producing a distinctive output voltage of one polarity at the beginning of each track code pulse and another distinctive output voltage of opposite polarity at the end of each track code pulse, circuit means including electron discharge tubes, selector means for connecting either said first or said second pulse-forming means between said receiver coils and said circuit means including said electron tubes, relay means including a two-position relay operable to either of its two different positions and operated alternately to its opposite positions in response to said distinctive voltages,
- 55 7. A cab signalling system for railroads comprising, a plurality of track sections with means for applying pulses of unidirectional current to the rails of certain of said track sections and additional means for applying pulses of alternating current to the rails of other of said track sections, said current pulses being applied to said rails at selected rates according to traffic conditions, vehicle-carried apparatus including receiver coils positioned adjacent the rails of said track sections, first pulse-forming circuit means including first tuning and damping resistance means responsive to said unidirectional track current for producing distinctive pulses of opposite polarity corresponding respectively to the beginning and end of each track code pulse, second pulse-forming means including second tuning and damping resistance means responsive to said alternating track current also for producing a distinctive output voltage of one polarity at the beginning of each track code pulse and another distinctive output voltage of opposite polarity at the end of each track code pulse, circuit means including electron discharge tubes, selector means for connecting either said first or said second pulse-forming means between said receiver coils and said circuit means including said electron tubes, relay means including a two-position relay operable to either of its two different positions and operated alternately to its opposite positions in response to said distinctive voltages,
- 60 8. A cab signalling system for railroads comprising, a plurality of track sections with means for applying pulses of unidirectional current to the rails of certain of said track sections and additional means for applying pulses of alternating current to the rails of other of said track sections, said current pulses being applied to said rails at selected rates according to traffic conditions, vehicle-carried apparatus including receiver coils positioned adjacent the rails of said track sections, first pulse-forming circuit means including first tuning and damping resistance means responsive to said unidirectional track current for producing distinctive pulses of opposite polarity corresponding respectively to the beginning and end of each track code pulse, second pulse-forming means including second tuning and damping resistance means responsive to said alternating track current also for producing a distinctive output voltage of one polarity at the beginning of each track code pulse and another distinctive output voltage of opposite polarity at the end of each track code pulse, circuit means including electron discharge tubes, selector means for connecting either said first or said second pulse-forming means between said receiver coils and said circuit means including said electron tubes, relay means including a two-position relay operable to either of its two different positions and operated alternately to its opposite positions in response to said distinctive voltages,
- 65 9. A cab signalling system for railroads comprising, a plurality of track sections with means for applying pulses of unidirectional current to the rails of certain of said track sections and additional means for applying pulses of alternating current to the rails of other of said track sections, said current pulses being applied to said rails at selected rates according to traffic conditions, vehicle-carried apparatus including receiver coils positioned adjacent the rails of said track sections, first pulse-forming circuit means including first tuning and damping resistance means responsive to said unidirectional track current for producing distinctive pulses of opposite polarity corresponding respectively to the beginning and end of each track code pulse, second pulse-forming means including second tuning and damping resistance means responsive to said alternating track current also for producing a distinctive output voltage of one polarity at the beginning of each track code pulse and another distinctive output voltage of opposite polarity at the end of each track code pulse, circuit means including electron discharge tubes, selector means for connecting either said first or said second pulse-forming means between said receiver coils and said circuit means including said electron tubes, relay means including a two-position relay operable to either of its two different positions and operated alternately to its opposite positions in response to said distinctive voltages,
- 70 10. A cab signalling system for railroads comprising, a plurality of track sections with means for applying pulses of unidirectional current to the rails of certain of said track sections and additional means for applying pulses of alternating current to the rails of other of said track sections, said current pulses being applied to said rails at selected rates according to traffic conditions, vehicle-carried apparatus including receiver coils positioned adjacent the rails of said track sections, first pulse-forming circuit means including first tuning and damping resistance means responsive to said unidirectional track current for producing distinctive pulses of opposite polarity corresponding respectively to the beginning and end of each track code pulse, second pulse-forming means including second tuning and damping resistance means responsive to said alternating track current also for producing a distinctive output voltage of one polarity at the beginning of each track code pulse and another distinctive output voltage of opposite polarity at the end of each track code pulse, circuit means including electron discharge tubes, selector means for connecting either said first or said second pulse-forming means between said receiver coils and said circuit means including said electron tubes, relay means including a two-position relay operable to either of its two different positions and operated alternately to its opposite positions in response to said distinctive voltages,
- 75 11. A cab signalling system for railroads comprising, a plurality of track sections with means for applying pulses of unidirectional current to the rails of certain of said track sections and additional means for applying pulses of alternating current to the rails of other of said track sections, said current pulses being applied to said rails at selected rates according to traffic conditions, vehicle-carried apparatus including receiver coils positioned adjacent the rails of said track sections, first pulse-forming circuit means including first tuning and damping resistance means responsive to said unidirectional track current for producing distinctive pulses of opposite polarity corresponding respectively to the beginning and end of each track code pulse, second pulse-forming means including second tuning and damping resistance means responsive to said alternating track current also for producing a distinctive output voltage of one polarity at the beginning of each track code pulse and another distinctive output voltage of opposite polarity at the end of each track code pulse, circuit means including electron discharge tubes, selector means for connecting either said first or said second pulse-forming means between said receiver coils and said circuit means including said electron tubes, relay means including a two-position relay operable to either of its two different positions and operated alternately to its opposite positions in response to said distinctive voltages,

and decoding means governed by said relay means and selectively operated according to the coding rate of the track current.

3. A cab signalling system for railroads comprising, a plurality of track sections, circuit means for applying pulses of unidirectional current to the rails of certain of said track sections and additional circuit means for applying pulses of alternating current to the rails of others of said track sections with said pulses applied at selected rates according to traffic conditions, first pulse-forming circuit means including first tuning and damping resistance means responsive to said unidirectional track current and second pulse-forming circuit means including second tuning and damping resistance means responsive to said alternating track current to provide distinctive voltage variations of opposite polarity corresponding respectively to the beginning and end of each code pulse, circuit means including electron tubes for amplifying said distinctive voltage variations, manually controlled means for selecting either said first or said second pulse-forming means to cooperate with said receiver coils and said amplifying means, relay means including a two-position relay operable to either of its two different positions and actuated by said amplifying means alternately to its opposite positions in response to said distinctive voltages, and decoding means selectively controlled by the rate of actuation of said relay means.

4. A cab signalling system for railroads comprising, a plurality of track sections with means for applying pulses of alternating current to the rails of said track sections at any one of various selected rates according to traffic conditions, train-carried apparatus including receiver coils mounted adjacent the track rails, tuning means connected with said receiver coils to resonate said coils to the frequency of said alternating track current, rectifier means associated with said receiver coils to rectify the alternating current in said coils, pulse-forming means including tuning and damping resistance means responsive to the unidirectional voltage provided by said rectifier means to produce distinctive voltage outputs of opposite polarity corresponding respectively to the beginning and end of each track code pulse, amplifier means including electron discharge tubes for amplifying said distinctive output voltages, relay means including a two-position relay governed by said amplifying means and being operated alternately between its two positions, and decoding means governed by said relay means and selectively operated according to the coding rate of said alternating track current.

5. In a cab signalling system for railroads, a plurality of track sections and means for applying pulses of alternating current to the rails of said track sections at different selected rates according to traffic conditions, vehicle-carried apparatus including receiver coils positioned adjacent the rails of said track sections, a first condenser and a rectifier connected in series with said coils to respectively tune said coils to the frequency of said alternating track current and to rectify the current through said coils, a transformer having its primary winding energized with the current rectified by said rectifier, a second condenser connected across the secondary winding of said transformer to thereby provide an oscillatory circuit having a natural frequency relatively low as compared to the usual commercial power frequencies, circuit means for damping the electrical oscillations of said tuned circuit as it responds to the unidirectional output voltage of said rectifier to provide distinctive output voltages of opposite polarity corresponding respectively to the beginning and end of each track code pulse, circuit means including electron tubes connected with said secondary winding for amplifying said distinctive output voltages, relay means including a two-position relay governed by said amplifier means and being operated alternately between said two positions, and decoding means selectively operated by said relay means according to the coding rate of the track current.

6. A cab signalling system for railroads including, a

plurality of track sections with means for applying pulses of unidirectional current to the rails of certain of said track sections and additional means for applying pulses of alternating current to the rails of others of said track sections with said current pulses being applied to said rails at selected rates according to traffic conditions, vehicle-carried equipment comprising receiver coils positioned in inductive relationship to said track rails, a first condenser to tune said receiver coils to a relatively low frequency as compared to the usual commercial power frequencies, damping means associated with said coils for damping the oscillations appearing across said coils so that a distinctive output voltage of one polarity is provided at the beginning of each code pulse and another distinctive voltage of opposite polarity at the end of each code pulse, a second condenser to tune said coils to the frequency of said alternating track current, a rectifier to rectify the alternating current in said coils, pulse-forming means including tuning and damping resistance means associated with said second condenser and rectifier to provide a distinctive output voltage of one polarity at the beginning of each track code pulse and another distinctive output voltage of opposite polarity at the end of each code pulse, manually operable means to connect said first condenser and said damping means with said coils when said vehicle is operated over track circuits energized with unidirectional track current and to connect said second condenser and associated rectifier and pulse-forming means with said coils when said vehicle is operated in regions of alternating current track circuit energization, amplifier means including electron tubes to amplify said distinctive output voltages, relay means including a two-position relay governed by the output of said amplifier means and being actuated alternately between its opposite positions at a rate corresponding to the coding rate of said track current, and decoding means selectively operated according to the coding rate of said track current.

7. In a cab signalling system for railroads, a plurality of track sections and means for applying pulses of alternating current to the rails of said track sections at selected rates according to traffic conditions, train-carried equipment comprising receiver coils mounted adjacent the track rails, a first condenser connected with said receivers to tune said receivers to the alternating track current frequency, a rectifier connected with said coils to rectify the alternating current through said coils to provide a unidirectional output voltage across said rectifier, a parallel-connected inductance and second capacitance tuned to a relatively low frequency as compared to the usual commercial power frequencies, circuit means connecting said rectifier output with said inductance to shock excite the tuned circuit formed by said inductance and said second capacitance by said unidirectional output voltages provided by said rectifier, means for damping the oscillations of said tuned circuit so that a distinctive output voltage of one polarity is provided corresponding to the beginning of each track pulse and another distinctive output voltage of opposite polarity is provided corresponding to the end of each track code pulse, amplifier means associated with said tuned circuit for amplifying said distinctive output voltages, relay means including a two-position relay controlled by said amplifier means and being operated alternately between its opposite positions, and decoding means selectively controlled according to the rate of track current coding.

8. A cab signalling system for railroads comprising, a plurality of track sections and means for applying pulses of alternating current to the rails of said track sections at different selected rates according to traffic conditions, train-carried apparatus including receiver coils mounted in inductive relationship to the track rails, a first condenser and a rectifier connected in series with said coils to respectively tune said coils to the frequency of said alternating track current and to rectify the current through

said coils, a parallel connected inductance and second capacitance, coupling circuit means for applying the unidirectional output voltage provided by said rectifier across said inductance to shock excite the tuned circuit formed by said inductance and second capacitance, circuit means for dampening the electrical oscillations of said tuned circuit thereby providing a distinctive output voltage of one polarity corresponding to the beginning of each track code pulse and another distinctive voltage of opposite polarity corresponding to the end of each track code pulse, trap circuit means including a series resonant circuit associated with said tuned circuit for removing undesired ripple voltages from the output voltages provided by said tuned circuit, circuit means including electron tubes connected with said tuned circuit for amplifying said distinctive output voltages, relay means including a two-position relay governed by said amplifying means and being operated alternately between its opposite positions, and decoding means selectively operated by said relay means according to the coding rate of the track current.

9. In a cab signalling system for railroads, a plurality of track sections with means for applying pulses of unidirectional current to the rails of certain of said track sections and additional means for applying pulses of alternating current to the rails of other of said track sections with said current pulses applied to said rails at selected rates according to traffic conditions, vehicle-carried apparatus including receiver coils positioned adjacent the rails of said track sections, first pulse-forming circuit means including first tuning and damping resistance means responsive to the unidirectional current for producing distinctive pulses of opposite polarity corresponding respectively to the beginning and end of each track code pulse, second pulse-forming means including second tuning and damping resistance means responsive to said alternating track current for producing distinctive output voltages of opposite polarity corresponding respectively to the beginning and end of each track code pulse, amplifier means comprising two channels of amplification with each of said channels including an electron tube biased to cutoff, manually operable selector means for connecting either said first or said second pulse-forming means between said receiver coils and said amplifier means, coupling circuit means for applying with opposite polarity respectively said distinctive output voltages between grid and cathode of said electron tube, relay means including a two-position relay operable to either of its two different positions and having two windings, a plate-cathode circuit of each of said electron tubes including a winding of said relay means whereby said relay means is actuated alternately between its opposite positions

- in response to said distinctive voltages, and decoding means governed by said relay means and selectively operated according to the rate of coding of said track current.
- 5 10. A cab signalling system for railroads comprising, a plurality of track sections with means for applying pulses of alternating current to the rails of said track sections at different selected rates according to traffic conditions, vehicle-carried apparatus including receiver coils positioned adjacent the rails of said track sections, 15 a tuning condenser and rectifier connected in series with said receiver coils to respectively tune said coils to the frequency of said alternating track current and to rectify the alternating current in said receiver coils, pulse-forming circuit means including, a discharge resistor connected across the output of said rectifier, two charging capacitors each having a terminal connected to a terminal of said discharge resistor, two equal series-connected resistors each having a terminal connected respectively to the remaining terminals of said charging capacitors, amplifier means including two electron tubes each having plate and cathode and control grid electrodes, coupling circuit means for applying the voltage across each of said equal resistors between the control grid and cathode of a corresponding electron tube, whereby at the beginning of each track code pulse said rectifier charges said charging capacitors to one polarity through said equal resistors to produce a momentary voltage output of one polarity across said equal resistors and at the end of each track 20 code pulse the drop of rectifier output voltage discharges said charging capacitors through said equal resistors and said discharge resistor to produce a momentary output voltage across said equal resistors of opposite polarity, code-following relay means including a two-position relay 25 controlled by said amplifier means and being operated alternately between its opposite positions, and decoding means selectively controlled by said relay means according to the rate of coding of said alternating track current.
